UNITED STATES PATENT OFFICE.

HARRY COHN, OF ALBANY, NEW YORK.

DUPLICATING-MACHINE.

1,342,530.

Specification of Letters Patent. Patented June 8, 1920.

Application filed March 20, 1919. Serial No. 233,863.

To all whom it may concern:

Be it known that I, HARRY COHN, a citizen of the United States, and a resident of Albany, in the county of Albany and State of New York, have invented a new and Improved Duplicating-Machine, of which the following is a full, clear, and exact description.

The invention relates to duplicating machines of the rotary printing drum type, and its object is to provide a new and improved duplicating machine arranged to permit of printing at each revolution of the printing drum the heading and the body of a letter, circular or other similar instrument with the heading appearing printed by inked type or inked electrotype and the body appearing printed in imitation of typewritten work by the use of an inked ribbon extending over the printing face of the body set up in typewriter type. Another object is to allow of the varying the height of the heading of the instrument.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a side elevation of the duplicating machine;

Fig. 2 is a front elevation of the same;

Fig. 3 is a cross section of the same on the line 3—3 of Fig. 2;

Fig. 4 is a perspective view of the segment detached from the printing drum;

Figs. 5 and 6 are face views of the sections of the cam controlling the inking rollers for the heading.

The duplicating machine is mounted on a suitable frame 10 in which is journaled the drum shaft 11 carrying the printing drum 12, and on the said drum shaft 11 is secured a crank arm 13 under the control of an operator for turning the drum. A rotary platen 14 journaled on the frame 10 cooperates with the printing drum 12 and rotates in unison with the same by the use of gear wheels 15 and 16 attached to the drum and platen, respectively, as shown in Fig. 2. Thus when the drum is rotated the platen rotates with it. The drum 12 is arranged

for supporting a printing segment 20 provided with holding means 21 for holding set-up type or an electrotype constituting a heading 22 for printing the heading of a letter, circular or similar instrument. The face of the heading 22 is inked at every revolution of the drum 12 by inking rollers 24 and 25 journaled in levers 26 and 27 on the frame 10 and provided with a friction roller 28 traveling on the peripheral face of a cam 29 rotating with the printing drum 12. Friction roller 28 has an extension shaft 28* on which lever 27 rests and lever 27 is connected by a spring 30 which holds lever 27 against extension shaft 28* and friction roller 28 in engagement with the cam 29. The rubber inking rollers 24 and 25 are in contact with steel oscillating rollers 40 and 41. Roller 41 receives a supply of ink from a rubber ductor roller 43 which travels back and forth between steel fountain roller 44 and steel roller 41. Between the rollers 40 and 41 is a rubber idler roller 42 which just touches the steel rollers 40 and 41 and completes the distribution function of the five forward rollers, 24, 25, 40, 41 and 42. Fountain roller (steel) 44 operates against adjustable fountain 45 which feeds a film of ink to fountain roller 44 and said film of ink is picked up by ductor roller 43 and carried to steel rollers 41. Levers 26 and 27 have expansions at their upper ends and are milled out to fit around inner sides of eccentric shaft knobs of rollers 24 and 25. Tightening screws run through the two expansions that extend beyond the knobs. The proper contact is first given to form rollers 24 and 25 against the type or electrotype by the adjustment of eccentric shafts of rollers 24 and 25 and then the screws in ends of expansions of levers 26 and 27 are tightened against the knobs of the shafts of rollers 24 and 25. During each revolution of the printing drum 12 a swinging movement is given to levers 26 and 27 in order to throw rollers 24 and 25 in contact with type face heading 22. When high portion of cam 29 operates against friction roller 28 inking rollers 24 and 25 are thrown away from heading 22.

In order to permit of holding the inking rollers 24 and 25 in contact with heading 22 of different height, the cam 29 is made in two sections 45 and 46 having projecting portions 47 and 48 for engagement by the friction roller 28 to move the inking rollers

24 and 25 in contact with the face of the heading 22. The cam sections 45 and 46 are adjustably fastened together by a bolt 49 engaging elongated slots 50 and 51 in the cam sections 45 and 46. By the arrangement described the aggregate length of the projections 47 and 48 can be varied to hold the inking rollers 24 and 25 in inking contact with the face of the heading 22 according to the height of the latter.

The segment 20 is further provided with holding means 60 for holding a body printing means 61 in the form of set-up type or electrotype. Over the body printing means 15 is stretched an inking ribbon 62 which passes through slots 63 and 64 formed in the segment 20 on the upper and lower ends of the body printing means. The inking ribbon 62 passes around guide rods 65, 66 and 67, 68 20 to wind at their ends on spools 69 and 70 journaled in the drum 12 and provided with the usual pawl and ratchet mechanisms for holding the inking ribbon stretched in place over the face of the body printing means 61 25 and to allow of changing such ribbon in the usual manner.

The operation is as follows:

A sheet of paper is fed between the printing drum 12 and its platen 14, and the drum 30 and platen are rotated by an operator turning the handle 13 or by an electric drive. It will be noticed that two impressions are made on the sheet, one by the heading 22 35 inked by the inking rollers 24 and 25 and one by the body printing means 61 through the medium of the inking ribbon 62. Thus the heading produced on the sheet is printer's printing while the body appears in imitation of typewritten work. It is expressly 40 understood that each sheet is printed with a heading in printer's printing and a body in imitation of typewritten work on each revolution of the printing drum 12.

The duplicating machine may be used 45 only for ink printing by dispensing with the inking ribbon, or only for printing in imitation of typewritten work by dispensing with the cam and inking rollers.

Having thus described my invention, I

claim as new and desire to secure by Letters 50 Patent:

1. In a duplicating machine, a rotary member provided with means carrying separate printing means, one for the heading and one for the body of the instrument to be printed, the said rotary member having slots one above and one below the said body printing means, a platen co-acting with the said rotary member, an inking ribbon extending through the said slots and over the printing face of the said body printing means, spools journaled in the drum and on which wind the ends of the said inking ribbon, inking rollers adapted to engage the face of the said heading printing means, levers to which said inking rollers are adjustably eccentrically pivoted, and a cam on the drum and controlling the said levers, the said cam being in adjustable sections to vary the movement of the lever according to the height of the said heading printing means.

2. In a duplicating machine, a rotary member provided with means carrying separate printing means, one for the heading and one for the body of the instrument to be printed, the said rotary member having slots one above and one below the said body printing means, a platen co-acting with the said rotary member, an inking ribbon extending through the said slots and over the printing face of the said body printing means, spools journaled in the drum and on which wind the ends of the said inking ribbon, inking rollers adapted to engage the face of the said printing means, levers to which said inking rollers are adjustably eccentrically pivoted, a roller at the opposite end of one of said levers, and engaged by the other of said levers, a cam on the drum 80 engaging said last named roller to control said levers, the said cam being in adjustable sections to vary the movement of the levers according to the height of the said heading printing means.

HARRY COHN.
